UNITED STATES PATENT OFFICE

ARTHUR R. CLARK, OF CHICAGO, ILLINOIS, ASSIGNOR OF ONE-HALF TO GEORGE J. KOHN, OF CHICAGO, ILLINOIS

LIGHTING FIXTURE

Application filed February 18, 1928. Serial No. 255,230.

This invention relates to improvements in lighting fixtures and it consists of the matters hereinafter described and more particularly pointed out in the appended claims.

- 5 Ceiling light fixtures as heretofore made include a ceiling plate from which depends a substantially bell shaped open bottom dome to which the neck of a glass shade or bowl is attached usually by thumb screws. 10 To clean the interior of the bowl or to renew the electric lamp or bulb used therewith it is necessary in this kind of a fixture to first loosen these screws before the globe can be removed, to give access to the interior of 15 the bowl or the lamp. This work is usually carried on from the top of a step ladder and renders the task somewhat difficult and in many cases results in dropping and breaking the bowl.
- 20 The primary object of the invention is to provide a fixture wherein the bowl may be readily brought into a position convenient for cleaning the interior thereof or renewing the lamp without a complete disconnection 25 between the dome and bowl in a manner preventing the dropping thereof during the cleaning of the same or the renewal of the lamp or light.

- A further object of the invention is to provide in such a fixture a bowl retaining ring which is hinged at one side to the dome and has means at the other side thereof whereby the ring may be locked to the dome to hold the bowl in its proper position with respect 35 thereto or may be manipulated to unlock the ring so that the same together with the bowl may be swung into an open position convenient for cleaning the interior thereof or for renewing the light or lamp in the dome. 40 These objects of the invention as well as the many advantages thereof will more fully appear as I proceed with my specification.

In the drawings:—

- 45 Fig. 1 is a view partly in side elevation and partly in section of a lighting fixture embodying the preferred form of my invention.

Fig. 2 is a horizontal sectional view as taken on the line 2—2 of Fig. 1.

50 Figs. 3 and 4 are detail vertical sectional

views on an enlarged scale through portions of the dome and bowl as taken on the line 3—3 and 4—4 respectively of Fig. 2.

Fig. 5 is a detail view in elevation showing the hinged connection between the dome 55 and bowl ring and which will be more fully referred to later.

Referring now in detail to that embodiment of the invention illustrated in the accompanying drawing, 1 indicates as a whole 60 a dome preferably made in two parts 2 and 3 hereinafter termed respectively the top and bottom parts. Each part has a neck of smaller diameter and each neck includes an inwardly extending annular flange 4 and 5 65 respectively, said flanges being secured together by screws 6 as best shown in Fig. 1. In the opening defined by said flanges is a lamp socket body 7 secured therein by a bushing 8 that screws on to the shell contact 70 of the lamp socket in the manner well known, said shell contact being adapted to have threaded into it, a lamp 9. The enlarged inverted base of the top part of the dome is adapted to be secured to a ceiling 10 in any 75 suitable manner while the enlarged open bottom end of the bottom part 3 of the dome is defined by an annular band portion or flange 11 of a diameter approximating the base of the top part of the dome. When a 80 lamp 9 is in the socket body 7, said lamp depends below the bottom edge of said flange 11. On the outside of the flange 11 at one side thereof, is a pair of laterally spaced ears 12—12 between which a portion of the flange 85 is removed for a purpose to appear later.

Associated with the flange 11 and normally positioned within the same is a ring 13 which constitutes the supporting element for a glass bowl 14. Said ring is a trifle smaller in diameter than said flange and while relatively thick is of a height less than said flange and is provided at a plurality of points on its top side with a plurality of pairs of upstanding bosses 15 and 16 respectively adapted to engage against an inturned shoulder 17 on the bottom dome part 3 at the top of said flange 11. Said ring is provided at a point between the bosses 15—15 with a lateral extension 18, which is disposed between and 100

- is pivoted to the ears 12—12 on the flange 11 by means of a pin 19. Diametrically opposite the extension 18, the ring has a notch 20 which opens through the bottom edge of the ring so that a thumb screw 21 threaded into the flange 11 may be caused to enter said notch to secure the ring in place within the flange. The bosses 15—15 each have an integral inwardly extending stud 15^a while the bosses 16—16 each carry a set screw 16^a. These set screws are flat headed and to accommodate them, the outer surfaces of the bosses and adjacent ring portions are flattened off as best shown in Fig. 2 to provide the necessary room for the heads of said set screws. The studs and screws just mentioned are adapted to so engage in the top flange portion or neck 14^a of the globe as to secure the same in the ring.
- 20 Assume that it is desired to clean the interior of the bowl or to change the lamp therein. As these operations are performed by a person on a step ladder, care of course is required and with the fixtures as heretofore made, the dropping of the bowl when removig the same was no uncommon occurrence. With my improved construction, it is only necessary to loosen the thumb screw 21 so as to withdraw its inner end from the notch 20 in the ring. The ring with the bowl retained therein is then swung downwardly about the hinge pin 19 as an axis into approximately the dotted line position shown in Fig. 1, thus presenting the interior of the bowl 25 for easy access or for the removal and renewal of the lamp 7. Thus there is no complete separation or disconnection between the dome and bowl and the bowl is hangingly supported from the dome in a manner preventing its accidental dropping but in a position convenient for either cleaning the bowl or renewing the lamp. After these operations have been carried out, the bowl is swung upwardly to bring the ring into its closed 30 position in the flange when the screw 21 is turned in the proper direction to enter the notch 20 in the ring and thus again lock the bowl in position therein.
- From the above, it is apparent that the 35 invention eliminates the usual breaking of the bowl attending such operations. The improved arrangement does not materially add to the cost of manufacture and as it is simple, it may be readily manipulated.
- 50 While in describing my invention, I have referred to many details as to form and arrangement of the parts thereof, the same is to be considered as by way of illustration only so that I do not wish to be limited thereto except as may be pointed out in the appended claims.
- 55 I claim as my invention:
1. A lighting fixture comprising a dome having an annular band portion at one end thereof, provided with spaced ears, a bowl

supporting ring normally positioned within said band portion and of a diameter smaller than said band portion and having an extension position between and hinged to said ears, a plurality of studs on said ring to engage in a part of the bowl and a thumb screw carried by the band portion opposite the hinge and adapted to releasably engage the ring. 70

2. A lighting fixture comprising a dome having an annular band portion, a bowl supporting ring normally positioned within and of a diameter smaller than said band portion, means providing a hinged connection between said band portion and one side of the ring, a plurality of studs and screws on said ring to engage in a part of said bowl and a thumb screw carried by the band portion opposite said hinged connection to releasably engage said ring. 75

3. A lighting fixture comprising a dome including an annular band portion with an inwardly extending annular shoulder at the top end thereof, a bowl supporting ring normally positioned within and of a diameter less than that of said band portion and hinged at one side thereto and means carried by the band portion opposite the hinge to releasably secure said ring within said band portion, said ring having arcuately spaced bosses on its top edge to engage said annular shoulder 80 to position said ring with its top edge spaced from said annular shoulder. 85

In testimony whereof, I have hereunto set my hand, this 9th day of February, 1928.
